C. H. HILL.
SAFETY STOP FOR SWITCHES.
APPLICATION FILED NOV. 13, 1915.

Patented May 21, 1918.

Inventor:
Charles H. Hill,
by *Alfred S. Davis*,
His Attorney.

UNITED STATES PATENT OFFICE.

CHARLES H. HILL, OF SCHENECTADY, NEW YORK, ASSIGNOR TO GENERAL ELECTRIC COMPANY, A CORPORATION OF NEW YORK.

SAFETY-STOP FOR SWITCHES.

1,267,222.

Specification of Letters Patent. Patented May 21, 1918.

Application filed November 13, 1915. Serial No. 61,393.

To all whom it may concern:

Be it known that I, CHARLES H. HILL, a citizen of the United States, residing at Schenectady, in the county of Schenectady, 5 State of New York, have invented certain new and useful Improvements in Safety-Stops for Switches, of which the following is a specification.

The object of my invention is to provide 10 a safety device for knife blade switches to prevent them from being closed accidentally. If a double throw knife blade switch is mounted so that the blades swing in a vertical direction there is a tendency for the 15 blades to fall and make contact when the switch is open. There is also danger that such switches will be accidentally closed by reason of carelessness on the part of the attendant. The more particular object of my 20 invention is to prevent accidents by reason of the closing of knife blade switches of the above-mentioned type at times when it is desired that they should remain open. It is not limited in its utility to this particu- 25 lar type of switch but may be employed with any form of knife blade switch irrespective of the way in which it is mounted.

My invention will best be understood by reference to the following description taken 30 in connection with the accompanying drawing in which I have shown a side view of a switch provided with one of my devices. As here shown the single pole double throw knife blade switch 1 has upper contact clips 35 2 and lower contact clips 3 mounted on the base 4 in such a way that the blade which is pivoted at 5 swings in a vertical direction. When the switch is open there is a tendency for the blade to fall and make 40 contact with the lower clips. This tendency increases after the switch has been in service for some time and the usual friction in the pivotal mounting has decreased. There is also danger that a careless attendant 45 will accidentally touch the handle 6 and close the switch on the lower contact. It has been customary heretofore to avoid this danger by providing separate blocks of insulating material which fit into the clips 50 3 and prevent the blade from making con-

tact therewith. Such blocks however are easily misplaced and lost and are therefore inefficient for providing the desired safeguard. This disadvantage is overcome by my device which comprises a blade 7 having 55 an insulating knob 8 on the end thereof and which is pivotally mounted at the point 9 adjacent the clips 3. When the switch is opened the device, which for convenience of description I term a safety stop, is placed 60 in the position shown in the drawing. The blade 7 is made to fit the contact clips 3 and its upward movement is limited by the usual shoulder 10, indicated by dotted lines, which is provided to limit the movement 65 of the switch blade toward the base. The safety stop is frictionally held in this position by the clips 3 and it will be apparent that it will be impossible to close the switch on the lower contacts until the safety stop 70 is manually thrown down to the position indicated by dotted lines where it does not interfere in any way with the operation of the switch.

While I have described and illustrated 75 the application of my invention to a single pole double throw switch, it will be apparent that a stop such as the one I have shown will be equally effective with switches having more than one pole and that it may be 80 applied to any knife blade switch, if desired, irrespective of the way in which it is mounted.

What I claim as new and desire to secure by Letters Patent of the United States, is:— 85

1. The combination with a switch having a knife blade and co-operating contact clips, of a safety stop comprising a blade pivotally mounted adjacent one of the contact clips and adapted to be held in position by said 90 contact clips when the switch is open and an insulating member on said blade adapted to limit the movement of the knife blade.

2. The combination with a switch having a knife blade and co-operating contact clips, 95 of means for limiting the motion of the knife blade toward the contacts comprising a member pivotally mounted adjacent one of the contact clips so as to swing in the same direction as the knife blade and adapted to 100

be held in position by the contact clips so as to limit the motion of the knife blade.

3. The combination with a switch having a knife blade and coöperating contact clips, 5 of a safety stop comprising a blade pivotally mounted adjacent one of the contact clips so that its path of travel is partly coincident

with that of the knife blade and adapted to be held in position by said contact clips so as to limit the movement of said knife 10 blade.

In witness whereof, I have hereunto set my hand this 12th day of November 1915.

CHARLES H. HILL.
